CLAIM

The ornamental design for a foldable box, as shown and described.

DESCRIPTION

FIG. 1 is a front perspective view of the foldable box according to our new design, shown in a folded and unassembled configuration;
 FIG. 2 is a front perspective view thereof, shown in a partially unfolded and unassembled configuration;
 FIG. 3 is a front perspective view thereof, shown in an unfolded and unassembled configuration;
 FIG. 4 is a front perspective view thereof, in a partially folded and assembled configuration;
 FIG. 5 is a front perspective view thereof, shown in a folded and assembled configuration with the lid open;
 FIG. 6 is a front perspective view thereof, shown with the lid in a closed configuration;
 FIG. 7 is a top plan view thereof;
 FIG. 8 is a front elevation view thereof;
 FIG. 9 is a bottom plan view thereof;
 FIG. 10 is a back elevation view thereof;
 FIG. 11 is a side elevation view thereof; and,
 FIG. 12 is an opposite side elevation view thereof.
